(57) **CLAIM**

The ornamental design for a connector housing, as shown and described.

DESCRIPTION

The present design is characterized in that the connector housing has eyed-flanges disposed between its forward and rear halves that are generally of reversed-T shape in cross section, wherein the top region of said housing is intended to receive one of the socket contacts, with the bottom region intended to receive the other socket contacts.

FIG. 1 is a top plan view;

FIG. 2 is a front elevation;

FIG. 3 is a bottom plan view;

FIG. 4 is a right-side elevation;

FIG. 5 is a rear elevation; and,

FIG. 6 is a perspective view of the housing, wherein the left-side elevation thereof symmetrical with the right-side elevation is not included.
